UNITED STATES PATENT OFFICE.

GEORGE H. BABCOCK, OF PLAINFIELD, NEW JERSEY.

DESIGN FOR A ROOFING-PLATE.

SPECIFICATION forming part of Design No. 21,367, dated March 8, 1892.

Application filed May 14, 1890. Serial No. 351,810. Term of patent 14 years.

To all whom it may concern:

Be it known that I, GEORGE H. BABCOCK, a citizen of the United States, residing at Plainfield, in the county of Union and State of New Jersey, have invented and produced a new and original Design for Roofing or Sheathing Tiles, of which the following is a specification, reference being had to the accompanying drawings, forming a part thereof.

10 The design relates to a clay or other tile, in which the ornamental architectural effects are produced by the contour, by the surface ornamentation of the tile, and by the association of the contour and the surface ornamentation.

15 In the drawings, Figure 1 illustrates a face view of a tile of the new design, and Fig. 2 illustrates a number of such tiles in an assembled condition laid in quincunx order,

20 illustrating the effect of the surface ornamentation and the effect of the latter in conjunction with the shape or outline of the tile.

The design relates particularly to the exposed or lower face of a tile, its upper portion 25 partaking of various shapes.

As illustrated, the tile has diagonal upper sides *a a*, which bear upper interlocking flanges. The lower or exposed portion of the tile has two straight sides *c c*, with an irregular lower side, the surface *A* of said lower portion being in the main a plain surface. The

surface ornamentation of the tile is composed of two curved figures *B C* upon the surface of the tile, which curved figures extend in opposite directions from the center of the tile toward the lower outer corners *d* thereof. The upper portions of each of the curved figures *B C* terminate in scrolls *e*. The lower portions of the curved figures *B C* conform and coincide with a portion of the outline of the lower edge of the tile, while that portion between the figures *B C* is of the spade form *f* shown. The surface of the tile may be otherwise ornamented by a conventional branch ornament *E*, as shown, extending into the spade form *f* at the lower portion of the tile, as shown in Fig. 2.

It may be stated that when a number of tiles are associated, as in Fig. 2, the contiguous curved figures forming a part of the surface ornamentation of the tile meet at the points *d* to form a greater curved figure, both ends of which terminate in the scrolls *e*, and that the outline at the lower edge of the tile forms a continuous undulating line, as shown. 55

What is claimed is—

The design for a tile, substantially as shown and described.

GEO. H. BABCOCK.
